US00D575900S

(12) **United States Design Patent**
Summerford et al.

(10) **Patent No.:** **US D575,900 S**
(45) **Date of Patent:** **** Aug. 26, 2008**

(54) **LUMINAIRE**

(75) Inventors: **Robert L. Summerford**, Selma, TX (US); **Claude Barozzini**, Macungie, PA (US); **Mike Joss**, Chicago, IL (US); **Bryan Huddleston**, San Marcos, TX (US)

(73) Assignee: **Genlyte Thomas Group, LLC**, Louisville, KY (US)

(**) Term: **14 Years**

(21) Appl. No.: **29/298,906**

(22) Filed: **Dec. 14, 2007**

Related U.S. Application Data

(63) Continuation of application No. 29/198,093, filed on Jan. 23, 2004, now Pat. No. Des. 561,932.

(51) **LOC (8) Cl.** **26-99**

(52) **U.S. Cl.** **D26/128**

(58) **Field of Classification Search** D26/142, D26/35, 46, 60, 61, 104, 113, 120, 123, 124, D26/136, 63, 138, 64, 80, 67, 37, 3, 28, 24, D26/122, 118, 88, 68, 85, 86, 87, 128; 362/648, 362/647, 427, 523, 240, 216, 84, 612, 558, 362/559, 555, 545, 311, 294, 249, 235, 307; D13/110, 133, 182, 180; 439/121, 118

CLAIM

The ornamental design for a luminaire, as shown and described.

DESCRIPTION

FIG. 1 is a perspective view of a luminaire showing the design;

FIG. 2 is a side view thereof;

FIG. 3 is a top view thereof; and,

FIG. 4 is a bottom view thereof.

The broken lines showing environmental structure are for illustrative purposes only and form no part of the claimed design.
